(57) **CLAIM**

The ornamental design for a wheelchair trainer, as shown and described.

DESCRIPTION

FIG. 1 is a perspective view of a wheelchair trainer showing my new design;

FIG. 2 is a top view thereof;

FIG. 3 is a front view thereof;

FIG. 4 is a back view thereof;

FIG. 5 is a left side view thereof;

FIG. 6 is a right side view thereof;

FIG. 7 is a bottom view thereof;

FIG. 8 is a perspective view thereof, showing a wheelchair mounted on the platform; and,

FIG. 9 is a right side view thereof.

The broken line showing is included for the purpose of illustrating portions that form no part of the claimed design. The broken line showing of the wheelchair in FIGS. 8 and 9 is included for the purpose of illustrating environment and forms no part of the claimed design.
